UNITED STATES PATENT OFFICE.

KIRK D. HOLLAND, OF CHICAGO, ILLINOIS.

VAPORIZING DEVICE.

Application filed September 10, 1921. Serial No. 499,647.

My invention relates to a device designed to produce in the highest degree possible complete volatilization of the heavier hydrocarbon elements of the fuel mixture used in explosive engines. The ordinary commercial gasoline now sold for use as fuel for automobile engines contains a larger percentage of the heavier hydrocarbons than that formerly used, and with the forms of carburetor generally in use these heavier constituents are not completely volatilized, but in part pass from the carburetor into the intake manifold and cylinders of the engine in the form of minute liquid particles which are but partially and imperfectly consumed in the process of combustion, the unconsumed portion collecting on the cylinder walls and diluting the lubricating oil and the imperfectly consumed portion giving rise to the production of carbon, with a resultant smoky exhaust and the formation of deposits of carbon at the valve seats and other parts of the engine in and adjacent to the explosion chambers of the engine. My present vaporizing device may be regarded as a modification and improvement of the device described in my earlier application for patent filed January 8th, 1920, Serial Number 350,143, and like that device is designed to be interposed in the intake passage of the engine between the carburetor and the intake manifold. My invention has for objects in view the production and perfecting of such a device to the highest state of perfection and efficiency in vaporizing the liquid particles of the carbureted mixture without heating the portion of the charge already vaporized, and in the initiation of the vaporizing action of the device and the efficient vaporization of such particles as speedily as possible after the engine begins running. In the appended claims I have pointed out more particularly the essential elements of my invention, it being understood that certain variations and modifications in the arrangement and construction of the members and elements recited are possible without departure from the spirit and substance of my invention.

In the accompanying drawing, illustrating my invention in a preferred form, Fig. 1 is a central vertical section of the device, showing adjacent portions of the associated carburetor and intake manifold of an ex-

plosive engine between which it is intended to be interposed, and Fig. 2 is a top view of the deflecting blades for producing a spiral motion in the stream of carbureted mixture passing through the device.

60

The same reference characters indicate the same parts in both figures of the drawing.

For convenience of manufacture, the casing of my novel vaporizing device is formed in two members, an outer base member 1, adapted to be secured by bolts 2 or other suitable means to the upper portion of the carburetor 3 of usual or suitable construction, and an upper and inner member 4 enclosing the central vaporizing chamber of the device and having at the bottom an extension which makes screw-threaded engagement with a central seat formed in the bottom wall of the base member. The inner member, it will be noticed, is formed with a shoulder bearing upon the adjacent top face of the base, the joint 5 between the two parts being sufficiently close to be substantially vapor tight. Below the joint 5 the base member is extended or curved outwardly to form the outer wall of an annular heating chamber 6, which, through the tubular boss 7 of the casing member 1 and a connecting pipe 8, is in communication with the exhaust manifold (not shown) of the engine. Diametrically opposite the boss 7, the base member of the casing is formed with an outlet 8, this outlet preferably being connected by a pipe 9 with a muffler (not shown), as in the device of my previous application above mentioned.

80

85

90

Above the joint 5 the wall of the upper casing member 4 is relatively thick, and at the top it is adapted to be secured to the intake manifold 10 of the engine, in the present instance a bolting flange 11 surrounding the outlet from the central chamber being formed at the top of the device, which flange is adapted to be secured to a bolting flange at the base of the manifold. Below the joint 5 a portion 12 of the inner member 4 which forms the inner wall of the heating chamber 6 is turned down to make it as thin as is compatible with a proper degree of strength. This wall 12 is continuous with an annular screw-threaded block 13 which constitutes the lower extension of the inner member 4 of the casing. The central orifice of the block 13 is formed with a seat to receive a tubular deflector support

100

105

110

14 which extends upwardly into the central chamber of the device to about the upper level of the annular heating chamber 6. Secured in the upper end of the support 14, 5 in the present instance by a spring ring 15 seated in an internal groove in the deflector support, is a deflector 16 having radiating, obliquely disposed fan-shaped blades arranged to impart a whirling or spiral motion to the stream of carbureted mixture passing from the carburetor to the intake manifold.

With the construction and arrangement of the parts of my device above described it 15 will readily be understood that the thin lower part of the wall of the central chamber of the device will almost immediately become heated by exhaust gases passing through the heating chamber 6 as soon as 20 the engine begins functioning, while the wall above the level of the heated zone so formed will remain cool. The deflector will impart a whirling or spiral movement to the carbureted mixture, and the heavier liquid particles of the stream will tend to fly upwardly and outwardly through the gasified portion, due to their greater weight and centrifugal motion. The result will be a winnowing or separating effect upon the liquid particles 25 causing them to fly outwardly and upwardly and impinge upon the inner face of the relatively cool unheated zone at the upper side of the central chamber in the member 4, where they will collect and drain downward- 30 ly to the heated lower portion of the wall and be volatilized and then be in condition to be drawn into the stream entering from the carburetor. That portion of the carbureted mixture already completely gasified 35 upon its entrance into the central chamber will pass directly from the deflector member to the outlet of the device, since it is directly and instantaneously subject to pressure conditions and influence, and as fast as they are 40 formed and drawn into the stream the same will be true of the gases resulting from the vaporization of the liquid particles. It will be observed that the heating chamber does 45 not extend inwardly at the bottom of the central chamber into proximity with the deflector support, and the latter therefore is 50 out of effective heat-conductive relation with such heating chamber.

The heat of the chamber 6 is therefore 55 applied only to vaporize the liquid particles of the charge, and since much of this heat becomes latent in producing the change of the particles from a liquid to a gaseous state, the temperature of the mixture passing to the intake manifold and engine cylinders is raised to a minimum degree, and its volumetric efficiency is not materially impaired.

Furthermore, my device is of such construction that its action is conducive to ease

and certainty of operation in starting a cold engine, even though a considerable proportion of kerosene or other relatively heavy hydrocarbons are present in the fuel. This will be understood when it is considered that in starting an engine, a very rich mixture is always employed (through manipulation of the "choker" button, or otherwise) and this over rich mixture frequently contains such a quantity of atomized, 70 but not vaporized, gasoline and kerosene, particularly the latter, that the spark plugs and cylinder are flooded with it, so that ignition is prevented. When my novel vaporizing device is employed, the liquid particles 75 are winnowed out and collect in the lower annular portion of the central chamber of the device around the deflector support 14, which thus constitutes a collecting chamber of ample capacity to receive the unvaporized portion of the carbureted mixture. Only the vaporized portion of the charge 80 passes to the engine cylinder and is employed in starting the engine, and it is only this part that can be consumed. The evil 85 effects of the liquid particles in preventing starting of the engine, as well as in other respects before explained, are thus avoided. As soon as the engine begins running the 90 heat in the chamber 6 acts to vaporize the accumulation of liquid fuel, and the device 95 functions as before explained.

I claim:

1. A vaporizing device for hydrocarbon engines comprising a casing formed with a central chamber having at its top an outlet 100 communicating with the intake passage of the engine and having at its bottom an inlet in alignment with said outlet and communicating with the carburetor, said chamber being enlarged and unobstructed between said 105 inlet and outlet and having an unheated upper zone and a heated lower zone and the wall of the chamber at said unheated zone having its outer surface exposed to the atmosphere, and helically inclined deflector blades in said inlet arranged to produce a spirally moving column of carbureted mixture 110 extending directly from said inlet to said outlet.

2. A vaporizing device for hydrocarbon engines comprising a casing formed with a central chamber having at its top an outlet 115 communicating with the intake passage of the engine, said chamber being enlarged and unobstructed between said inlet and outlet and having an unheated upper zone and a heated lower zone, a tubular deflector support extending into said chamber and having an inlet passage communicating with the carburetor, and a deflecting device arranged 120 in said inlet passage, said deflector being arranged to impart a spiral motion to the stream of carbureted mixture.

3. A vaporizing device for hydrocarbon 125

engines comprising a casing formed with a central chamber having at its top an outlet communicating with the intake passage of the engine, said chamber having an unheated upper zone and a heated lower zone, a tubular deflector support extending upwardly into said chamber to a plane adjacent the line between the heated and unheated zones of such chamber, and a deflecting device secured in said support at the top thereof and having blades arranged to impart a spiral motion to the stream of carbureted mixture.

4. A vaporizing device for hydrocarbon engines comprising a casing formed with a central chamber having at its top an outlet communicating with the intake passage of the engine and having at its bottom an inlet communicating with the carburetor, said chamber being enlarged and unobstructed between said inlet and outlet and said casing being also formed with an annular heating chamber surrounding the lower portion only of said central chamber and in communication with the exhaust passage of the engine, the casing wall around said central chamber above said annular heating chamber having its outer surface exposed to the atmosphere, and helically inclined deflector blades in said inlet arranged to produce a spiral column of carbureted mixture extending directly from said inlet to said outlet.

5. A vaporizing device for hydrocarbon engines comprising a casing forming with a central chamber having at its top an outlet communicating with the intake passage of the engine and also formed with an annular heating chamber surrounding the outer lower portion only of said central chamber, said heating chamber being in communication with the exhaust passage of the engine, and a tubular deflector support extending into said central chamber concentrically of said heating chamber and out of effective heat-conductive relation therewith, said support having an inlet passage communicating with the carburetor and being equipped with obliquely set deflector blades.

6. A vaporizing device for hydrocarbon engines comprising a casing formed with a central chamber having at its top an outlet communicating with the intake passage of the engine and also formed with an annular heating chamber surrounding the outer lower portion only of said central chamber, said heating chamber being in communication with the exhaust passage of the engine, and a tubular deflector support extending into said central chamber concentrically of said heating chamber and out of effective heat-conductive relation therewith, said support having an inlet passage communicating with the carburetor and terminating adjacent the plane of the top of said heating

chamber and being equipped adjacent its upper end with obliquely set deflector blades.

7. A vaporizing device for hydrocarbon engines comprising a casing formed with a central chamber having at its top an outlet and at its bottom an inlet communicating respectively with the intake passage of the engine and the carburetor, said casing being also formed with an annular heating chamber surrounding the outer lower portion only of said central chamber and the wall between said central chamber and said heating chamber being relatively thin, the casing wall around said central chamber above said annular heating chamber having its outer surface exposed to the atmosphere, and helically inclined deflector blades arranged adjacent the inlet to said chamber to produce a spiral column of carbureted mixture extending directly from said inlet to said outlet, said central chamber being enlarged and unobstructed between said deflecting means and the outlet of such chamber.

8. A vaporizing device according to claim 7 in which the central chamber is formed in a casing member having an upper section arranged with its outer surface exposed to the atmosphere and having a lower inner section, and in which a lower casing member surrounding said lower inner section of said first-mentioned casing member and extending outwardly therefrom is arranged to provide an annular recess constituting the heating chamber.

9. A vaporizing device according to claim 7 in which the central chamber is formed in an upper and inner casing member, and in which a lower casing member surrounding said upper member and extending outwardly therefrom is arranged to provide an annular recess constituting the heating chamber, said inner member being of reduced thickness opposite said recess.

10. A vaporizing device according to claim 7 in which the central chamber is formed in an upper and inner casing member, and in which a lower casing member surrounding said upper member and extending outwardly therefrom is arranged to provide an annular recess constituting the heating chamber, said inner member being formed with a screw-threaded annular block arranged to engage a screw-threaded orifice formed at the bottom of said outer member.

11. A vaporizing device according to claim 7 in which the central chamber is formed in an upper and inner casing member, and in which a lower casing member surrounding said upper member and extending outwardly thererfrom is arranged to provide an annular recess constituting the heating chamber, said inner member being formed with a shoulder adapted to cooperate

with the upper adjacent face of said lower member and also formed with a screw-threaded annular block arranged to engage a screw-threaded orifice formed at the bottom of said inner member to clamp said members together.

12. A vaporizing device for hydrocarbon engines comprising casing members formed with a carbureted mixture passage including an upper unheated portion and a lower tubular inlet portion and an annular collecting chamber surrounding said inlet portion

and communicating with said upper portion, means for heating said collecting chamber, and helically inclined deflector blades arranged to produce a spirally moving column of carbureted mixture, whereby liquid particles in the mixture will emerge tangentially from such column and impinge upon the wall of the unheated upper portion of the passage and drain into said heated collecting chamber.
